METHOD OF MAKING SHOES

William Thomas Buckingham Roberts, Leicester,
England, assignor to United Shoe Machinery
Corporation, Borough of Flemington, N. J., a
corporation of New Jersey

Application January 13, 1938, Serial No. 184,853
In Great Britain February 1, 1937

3 Claims. (Cl. 12—145)

This invention relates to shoes and to methods of making the same and particularly to shoes in which the upper materials, in whole or in part, are cement-lasted to the insole.

Objects of the invention are to provide a method of making shoes whereby wrinkling of the vamp lining is avoided and the various layers of upper material at the toe of the shoe may be worked over the insole and properly secured thereto without causing undesirable pleating and bunching of the upper materials at the toe, thus avoiding the trimming and flattening operations which are frequently performed, particularly when the uppers of narrow toed shoes are secured in lasted position with cement.

With these objects in view, the upper materials, in the practice of the illustrated method, are worked over an insole upon a last bottom in two steps. First, the vamp lining and toe box are placed upon the forepart of the last and their marginal portions worked into lasted position over the insole. Thereafter the remaining portions of a shoe upper comprising usually but not necessarily the entire outer layer of the upper, a quarter lining and a counter are assembled upon the last, pulled over and their marginal portions worked over the insole at the heel and shank and over the already lasted vamp lining and box at the forepart of the shoe. Since by this procedure the rear edge of the vamp lining is exposed inside the shoe, the quarter lining is preferably made to extend around the throat of the shoe and, after the last is removed, the rear edge of the vamp lining is tucked under the forward edge of the quarter lining and cemented thereto so that the free rear edge of the vamp lining, which is usually of fabric, will be covered up and will not interfere with the introduction of the foot.

In order that the vamp lining and box may be worked over the insole smoothly and evenly, the toe end of the insole, preferably and as illustrated herein, is skived, beveled or otherwise reduced in thickness and the vamp lining is reduced in length around the toe end to provide only a narrow lasting allowance. The toe box, which is of usual size, therefore extends beyond the vamp lining around the toe. The toe box may be of well-known material obtainable under the trade name "Celastic" which can be softened and activated with suitable solvent. The vamp lining and box are then conformed to the toe portion of the last and their marginal portions worked over the bottom of the insole and secured in lasted position by means of ce-

ment, the vamp lining and toe box being so proportioned that at the toe of the shoe the vamp lining will extend partly over the beveled or reduced portion of the insole and the box will extend over the vamp lining and over the remainder of the reduced portion of the insole. Thus, the vamp lining and box around the toe merely take the place of the portion of the insole removed in reducing it and no objectionable pleats or bunches are formed. Thereafter the remainder of the upper comprising, for example, the outer layer, a doubler, a quarter lining and counter, are assembled in the usual manner over the insole including the already lasted vamp lining and box, the upper pulled over and the remaining portions of the lasting allowance worked into lasted position and secured in any usual or desired manner. Preferably the lasting allowance of the doubler at the toe of the shoe is made shorter than the upper or is reduced by roughing or otherwise so that only a narrow margin of it extends over the box between the box and the upper so that the lasting allowance of the upper, which is of usual width, may be readily cemented to the box and vamp lining.

These and other objects and features of the invention will appear more fully from the following detailed description when read in connection with the accompanying drawings and will be pointed out in the appended claims.

In the drawings:

Fig. 1 is a perspective view of an insole for use in the illustrated method;

Fig. 2 is a perspective view showing the vamp lining and toe box assembled together;

Fig. 3 is a perspective view showing the vamp lining and toe box worked over an insole upon a last;

Fig. 4 is a sectional view taken on the line IV—IV of Fig. 3;

Fig. 5 is a perspective view of a closed shoe upper ready to be assembled with the last, insole, vamp lining and box as shown in Fig. 3;

Fig. 6 is a perspective view showing the upper of Fig. 5 assembled upon the last with the shoe parts shown in Fig. 3, and side lasted;

Fig. 7 is a perspective view similar to Fig. 6 showing the toe and heel lasted;

Fig. 8 is a longitudinal median section of the forepart of the shoe shown in Fig. 7; and

Fig. 9 is a longitudinal section of the toe portion of the shoe after the sole has been attached and the rear margin of the vamp lining tucked under the forwardly projecting portion of the quarter lining.

In carrying out the illustrated novel method of making shoes, an insole 10 is cut to fit the bottom of a last and has its marginal portion on its outer face at the toe end reduced in thickness, beveled or skived, preferably as shown at 12 in Fig. 1.

A vamp lining 14 and a toe box 16 are prepared and assembled as shown in Fig. 2. The toe box 16 may be of the well-known material disclosed in Letters Patent of the United States No. 1,256,240, granted February 12, 1918, on an application of Stanley P. Lovell, and sold under the trade-mark "Celastic." This material comprises a fabric base charged with pyroxylin or Celluloid in precipitated condition which can be readily activated by a suitable solvent. The vamp lining 14 may be of usual lining material and of substantially the usual shape, the toe portion, however, being cut back along the line 18 so that when the toe box 16 and vamp lining 14 are superimposed in their usual relation, as shown in Fig. 2, the marginal portion of the toe box 16 will be exposed beyond the line 18 of the vamp lining. The insole 10 is placed upon a last 20, and the vamp lining 14 and toe box 16, the latter being first activated by dipping it in a pyroxylin solvent, are placed upon the last 20 and the marginal portions worked over the insole as shown in Figs. 3 and 4. The marginal portion of the vamp lining 14 at the toe, being cut back as described, extends only part way over the beveled portion 12 of the insole 10 while the toe box 16 extends beyond the vamp lining and covers the reduced portion 12 of the insole. The lining and box together substantially replace the material removed from the insole so that the shoe bottom at the toe end is again level, as shown in Fig. 4. In conforming the vamp lining and toe box to the last, apparatus such as that disclosed in Letters Patent of the United States No. 2,079,716, granted May 11, 1937, on an application of Joseph Prosper, may be employed, this apparatus comprising a form fitting the toe portion of the last and a pair of wipers so arranged that after the toe end of the last has been forced against the form to conform the upper materials to the shape of the last the marginal portions projecting above the last may be wiped into lasted condition against the insole. Before this operation, however, the margin of the insole at the forepart and the vamp lining should be treated with a suitable cement which, if a "Celastic" toe box is used, may well be a pyroxylin cement and which, in any event, should be a cement which will adhere to the material of the toe box. Thus, when the marginal portions of the vamp and toe box are brought into lasted relation to the insole they will adhere thereto. It is to be understood that the "Celastic" box toe material while activated has cementitious properties and will adhere to the portion of the insole with which it contacts. To prevent sticking of the box toe material to the form during this operation French chalk or a thin layer of paper or cloth may be applied to the mold. After the cement has set and the shoe is in the condition shown in Fig. 3, the overlasted portion of the vamp lining and toe box may be buffed if desired to even the shoe bottom surface.

In Fig. 5 is shown a closed shoe upper comprising a vamp 22, a quarter 24 (secured together by a seam 26, Fig. 6), a quarter lining 28 and a doubler 30, the latter being, for example, of loose fabric such as cotton flannel ad-

hesively secured to the inner surface of the vamp 22. The outer layer, comprising the vamp 22 and quarter 24, are sewed together to the quarter lining 28 at 32 around the top of the upper. The quarter lining extends forwardly beyond the line of stitching at the throat of the upper to form a flap 34. The toe portion of the doubler 30 may be cut back or frayed, for example by a wire brush, so that but little of its lasting allowance will remain to be worked over the shoe bottom.

After placing a counter 36 (Fig. 7) in the upper shown in Fig. 5, the upper is worked over the last 20 upon which the other shoe parts are already lasted, as shown in Fig. 3, and the upper pulled over as usual. The sides of the shoe and the heel-seat can then be lasted in any usual or desired manner, for example with tacks 38 (Fig. 6), staples 40 (Fig. 7) or cement. The toe end portion of the upper 22 is preferably lasted with a machine having end-embracing wipers, for example a bed lasting machine. Prior to this operation a suitable adhesive will be applied to the marginal portion of the inner face of the outer layer 22, 24 of the upper and to the overlasted 25 marginal portions of the vamp lining 14 and box 16, rubber latex adhesive being suitable for this purpose. It will be understood that in effecting the toe lasting operation at this stage the inward wiping of the single outer layer 22, 24 30 can be carried out much more readily than when a plurality of layers of upper materials have to be lasted in one operation, the operation being directly facilitated by the smooth, even character of the shoe bottom over which the outer layer 22, 24 is to be wiped. After the toe lasting operation the shoe, as shown in Fig. 7, has the lasting allowance laid over very smoothly and evenly around the toe of the shoe without objectionable pleats or other upstanding material that would interfere with the laying of an outsole on the shoe. A suitable filler 42, equivalent to the outer layer 22, 24 in thickness, may be employed and an outsole 44 laid upon the shoe bottom and secured thereto by the well-known cement sole attaching operation or by through-and-through stitches 46, as shown in Fig. 9.

As shown in Fig. 8, the vamp lining 14, before the last is withdrawn, is in contact with the last, the flap 34 of the quarter lining lying outside of the vamp lining 14. If the parts remain in this relation the forward edge of the vamp lining 14 might be caught by a foot being introduced into the shoe. Accordingly, after the last is withdrawn, the flap 34 of the quarter lining is pulled rearward and the free rearward edge of the vamp lining 14 tucked beneath it, suitable cement being applied so that when the flap 34 of the quarter lining is pushed forwardly over the vamp lining the parts will be permanently held in that position. If necessary, a short slit may be made at each side of the marginal portion of the vamp lining near the upper edge of the insole more readily to permit the above indicated rearrangement of the vamp and quarter linings.

Having thus described my invention, what I claim as new and desire to secure by Letters Patent of the United States is:

1. That improvement in methods of making shoes which consists in assembling an insole, a separate vamp lining and a toe box upon a last, conforming the vamp lining and toe box to the toe portion of the last and working their marginal portions into lasted position over the insole, thereafter assembling upon the last a complete 75

- closed upper, a quarter lining which extends across the throat of the upper and a counter, working the marginal portion of a quarter and quarter lining into lasted position over the insole 5 and securing them thereto, working the marginal portions of the vamp over the marginal portions of the vamp lining and toe box, securing them in lasted position, and locating the front edge of the quarter lining next to the wearer's foot.
- 10 2. That improvement in methods of making shoes which consists in assembling an insole, a vamp lining and a toe box upon a last, conforming the vamp lining and toe box to the toe portion of the last and working their marginal portions into lasted position over the insole, thereafter assembling upon the last a complete closed upper, quarter lining and counter, working the marginal portions of a quarter and quarter lining into lasted position over the insole and securing them thereto, working the marginal portions of the vamp over the marginal portions of the vamp lining and toe box and securing them in lasted position, securing a sole to the overlaid marginal portions of the upper, removing the 15 last, and tucking the rear edge of the vamp lining under the forward edge of the quarter lining.
- 20 3. That improvement in methods of making shoes which consists in providing an insole having its marginal portion reduced about the toe, providing a vamp lining having its lasting allowance reduced in width or cut back about the toe portion, arranging a toe box in relation to the vamp lining so that the margin of the toe box extends beyond the edge of the vamp lining in the cut-back portion, arranging the insole, vamp lining and toe box upon a last, conforming the vamp lining and box to the last, wiping the marginal portions of the vamp lining and box over 25 the reduced portion of the insole whereby the marginal portions of the vamp lining and toe box occupy the position of the material removed in reducing the insole and the shoe bottom is substantially level, assembling upon the last a complete outer layer of upper material, a counter, a quarter lining which extends forwardly beyond the throat of the upper and a vamp doubler, working the marginal portions of the thus-assembled upper materials over the shoe bottom 20 and securing them in lasted position, attaching a sole to the shoe, tucking the rear edge of the vamp lining under the forward projection of the quarter lining, and cementing the quarter lining 25 to the vamp lining.
